UNITED STATES PATENT OFFICE.

SIMIEON J. SCHINORENBERG AND GEORGE SIMPSON, OF OSHKOSH, WISCONSIN.

SEWING-MACHINE ATTACHMENT FOR MAKING DRESS-FACING.

SPECIFICATION forming part of Letters Patent No. 579,014, dated March 16, 1897.

Application filed July 10, 1896. Serial No. 598,747. (No model.)

To all whom it may concern:

Be it known that we, SIMIEON J. SCHNOR-
ENBERG and GEORGE SIMPSON, citizens of the
United States, residing at Oshkosh, in the
5 county of Winnebago and State of Wisconsin,
have invented certain new and useful Im-
provements in Sewing-Machine Attachments
for Making Dress-Facings; and we do declare
the following to be a full, clear, and exact
10 description of the invention, such as will en-
able others skilled in the art to which it ap-
perts to make and use the same, reference
being had to the accompanying drawing, and
to the letters of reference marked thereon,
15 which forms a part of this specification.

Our invention relates to a sewing-machine
attachment for the making of dress-facing.
Dress-facing is a new article of manufacture,
and is sold in the market by the yard, ready
20 to be put around the bottom of ladies' dresses,
and is intended to take the place of binding
formally used upon dresses. It consists of a
strip of waterproof or other similar material
folded or doubled together, to which is sewed
25 another strip of analogous material, adapted
to extend upwardly from the bottom beneath
the skirt and to be attached thereto by blind
stitching or otherwise.

Our invention consists, essentially, of a
30 folder or doubler to fold or double the strip of
waterproof material and guide it to the needle
of the machine and a gage above the folder
to guide the other strip of analogous material
properly in relation to the folded strip, so
35 that they may be sewed together in a proper
manner, as will be hereinafter described and
specifically claimed. The folded strip extends
below the bottom of the dress and acts as a
dress-protector. The strip that is sewed to
40 the protector is the facing proper to the dress
and may extend upwardly to any desired ex-
tent for the purpose of facing or stiffening the
dress. The gage for the facing is separate
from the folder and is adjustable laterally.

45 We have shown in the accompanying draw-
ing a form of our invention employing an
adjustable gage for the facing.

The drawing shows a perspective view of
our improved device. Both materials are

first cut into strips and wound upon spools 50
and fed to the sewing-machine from the spools.

Our invention may be either right or left
handed, accordingly as the folder and gage
are attached to the connecting-plate.

The attaching-plate of the folder is se- 55
cured to the bed of the machine by the thumb-
screw *a*, operating in the slot *a'* in the same
manner that sewing-machine attachments
are usually connected and adjusted.

B is the folder, having an opening to receive 60
the strip of material or braid from the spool,
the opening operating to fold the material
around the longitudinal projection in the
folder B, thus folding the material or braid
before it reaches the needle of the machine. 65
The walls of the opening operate as a gage
to guide the doubled strip properly to the
needle. The facing-strip is fed from a spool
and passes to the needle above the folded
strip, as shown in the drawing, and is guided 70
thereto by the gage E.

In the illustration the gage E is adjustable
by means of a thumb-screw *a*, so that it may
be moved laterally to press against the edge
of the facing-strip and properly guide it as it 75
is drawn along, being fed to the machine.

Our device is particularly well adapted for
the purpose of folding soft material as well
as material of a stiffer texture.

Having thus described our invention, what 80
we claim to have invented, and desire to se-
cure by Letters Patent, is—

1. In a sewing-machine attachment for pro-
ducing dress-facing, the combination of a
braid-doubling portion closed except at its 85
ends, by a solid immovable wall, and an aux-
iliary gage wholly exterior to said doubling
portion and disconnected from the same and
adapted to be adjusted with respect to the
doubling portion on a line at right angles to 90
the line of movement of the work, and a
thumb-nut for holding the gage in a fixed
position, substantially as described.

2. In a sewing-machine attachment for pro-
ducing dress-facing, the combination of a 95
braid-doubling portion closed except at its
ends by a solid immovable wall, a stationary
projecting rib on said wall longitudinal to

the same, and an auxiliary adjustable gage wholly exterior to said doubling portion and disconnected from the internal guiding-rib of the doubling portion so as not to be affected by the work passing through the doubling portion and a thumb-nut for holding the gage in an adjustable position, substantially as described.

In testimony whereof we affix our signatures in presence of two witnesses.

SIMIEON J. SCHNORENBERG.
GEORGE SIMPSON.
